CIRCUIT BREAKER ARRANGEMENT FOR
ELECTROMAGNETICALLY OPERATED
RECIPROCATING DEVICESAnton Voros, Jr., Allen Park, Mich., assignor of
one-half to Stephen J. Voros, Allen Park, Mich.

Application May 16, 1946, Serial No. 670,106

3 Claims. (Cl. 172—126)

1

This invention relates to circuit making and breaking devices for electromagnetically operated reciprocating mechanisms and it has for its primary object to provide a coupling between the members controlling the energization of the electromagnetic coils and the reciprocating members, which permits intermittent operation and idle motion of the positively moved coupling members within the members controlling the energization, which coupling uses means for producing said intermittent coupling which are easily adaptable to different types of mechanisms and to different strokes of the reciprocating members and which are easily adjustable in order to obtain greatest precision.

A further object of the invention consists in providing a circuit making and breaking device of the character above indicated of great simplicity, operating with a minimum of moving or movement transmitting parts, which device is positive and automatic in its operation and at the same time is self-contained and reliable, and may be finely adjusted for action at predetermined phases of operation.

A still further object of the invention consists in providing a circuit breaker construction which will produce a pressure at the contacts which is sufficient for perfect contact and safe operation.

Further objects will become apparent in the course of the following detailed specification.

The invention is illustrated in the accompanying drawing showing one embodiment thereof. It is, however, to be understood that this embodiment is merely one example intended to illustrate a practical application. The invention is described and illustrated in such a manner that further embodiments may be constructed without difficulty by persons skilled in this art and these further embodiments which have been foreshadowed by the following specification, as far as included in the annexed claims, are therefore part of the invention and do not constitute departures therefrom.

In the accompanying drawing:

Figure 1 is an elevational sectional view through a reciprocating mechanism such as a diaphragm pump driven by a solenoid or magnet arrangement whose armature is reciprocated by means of a circuit making and breaking arrangement according to the invention.

Figure 2 is an elevational side view of this arrangement.

Figure 3 is a sectional plan view of the same arrangement, the section being taken along line 3—3 of Figure 1, with the magnet coil removed.

2

Figure 4 is an elevational view of the casing housing the contact slide.

Figure 5 is a front view and side view of the contact slide.

5 It will be understood that the invention comprises essentially the circuit making and breaking arrangement and its combination with the electromagnetically operated driving mechanism but is not connected with the mechanism driven 10 thereby. For the sake of illustrating one practical example a diaphragm pump of the type used for fuel pumps was arbitrarily selected. This driven device is not of influence on the driving electromagnetic device with its circuit breaker 15 and is, therefore, merely briefly described. It may be replaced by any other reciprocating mechanism.

The arrangement shown in Figure 1 comprises a casing 5 fixed on the diaphragm pump 6, which 20 comprises, as usual, a diaphragm 7, held on a plunger 8, a pressure chamber 9, a pressure valve 10, a delivery chamber 11, a delivery or outlet opening 21, a fluid admission chamber 12, a suction chamber 13, a suction valve 14, and an admission opening 23, all these parts arranged and operating in a well known manner.

The plunger 8 is screw-threaded and carries nuts 15 clamping an arm 16. Its end is screwed into the core 18 of a solenoid or electromagnet 20. 30 The core is under the influence of a spring 22 finding its base in a plug or socket 24.

The electromagnet comprises a coil 25 fixedly mounted within the casing, whose circuit is to be controlled, in order to produce a reciprocating motion of the core 18.

35 This control of the circuit of the solenoid or electromagnet 20 is performed by means of the circuit making and breaking arrangement designated in general by the reference numeral 30. It consists of the arm 16 carried by plunger 8 by means of nuts 15, whose free end enters through opening 23 into the interior of a sleeve-like guide tube or slide carrier 32 of square or rectangular cross section which is fixedly 45 mounted on the pump body 6 by means of projecting foot members 34 and screws 36 (Figures 1 and 4).

On its upper end the guide tube or slide carrier 32 is provided with a laterally projecting bracket 38 which, by means of insulating washers 33 carries a contact spring 40, having a pre-selected resiliency or elasticity. At the end of the spring a contact 41 is mounted.

In the hollow interior of the guide tube 32 a 55 slide 44 is movable which consists, as shown in

Figures 1 and 5, of a metal strip with a U-shaped bent portion 42 which fills the entire section of the guide tube 32, so that the straight portion glides on one side thereof while the bent portion glides on the opposite side.

It will be seen from Figure 1 that the bent or retracted portion 42 causes the formation of a gap or cavity 48 in the slide into which the arm 16 enters.

Through the side walls of the bent portion, set-screws 49, 50 are projecting, which cooperate with the end of arm 16. The width of the gap and the distance between the set-screws which is finely adjustable determine the extent to which the arm may travel without moving the slide and thereby determine the length of the piston stroke.

The end of the slide 32 is bent (at 46) and is provided with an insulated contact 47 which cooperates with contact 41 on spring 40.

To hold the slide 44 in its correct position within the guide tube 32 during its movement a spring 52 is provided which presses against the straight portion of the slide. This spring not only holds the slide in its correct position in which the straight parts are lying flat on the guide but by virtue of the friction produced by the pressure also holds the slide in whatever position into which it may have been shifted. In order to avoid displacement of the spring small tongues 53 may be punched out in the guide tube near the upper end thereof and may be bent inwardly, so as to form a support for the spring.

The operation of the device will be clear from the foregoing detailed description. When the plunger 8 is moved downwardly the arm 16 reaches the set-screw 49 and moves the contact 47 towards contact 41 on spring 40. It will be noted that spring 40 is somewhat depressed during the last phase of the downward movement so that it presses the contacts firmly against each other, preventing imperfect contact between the same.

When the contacts 41 and 47 close the circuit of the solenoid magnet 20, the latter attracts core 18, thus starting an upward movement. The circuit of the magnet is, however, not interrupted during the first phase of such movement as arm 16 moves within gap 48 without moving the slide. Finally, near the end of the stroke arm 16 strikes against screw 50 and entrains slide 44. The slide, in moving upwardly, moves contact 47 away from contact 41 and spring 40 whereby the circuit of the solenoid is interrupted. Spring 22 moves the core downwardly and the cycle starts again. When the circuit breaker is at rest, the spring 22 holds the arm 16 in its lowermost position and, therefore, holds contacts 47 firmly in engagement, thus holding the device in readiness for immediate further operation.

It will be seen from the above that the circuit breaking device according to the invention operates safely with a minimum of moving parts, and permits adjustment of the stroke individually as well as adjustment for different types of solenoid magnets. It is especially adapted for mass production.

It is also to be understood that the foregoing description, while giving specific rules of construction, intends to outline the principles involved so that it will be manifest to experts that the parts, members and devices specifically described may undergo many constructive changes without, however, leaving the outlined principle on which the invention is based.

I claim:

1. In a reciprocating electromagnetic driving device provided with a solenoid, having an operative circuit and a magnetically permeable core member under spring pressure, and a circuit making and breaking device controlled by the movement of said core member and controlling the operative circuit of the solenoid, said device comprising a slide member arranged in substantial parallelism to the axis of the core member of the solenoid and provided with a slide surface having a U-shaped recessed portion, said recessed portion being open towards said core member and having a bottom surface substantially parallel to the aforesaid slide surface, a closed tubular guide member, provided with parallel slide surfaces, cooperating with the two before mentioned slide surfaces, enclosing and guiding said slide member, said tubular member being provided with an opening on the side facing the core member, said opening uncovering the recessed portion of the slide member, an arm projecting from said core member through said opening and the tubular guide member into the recessed portion of the slide, centrally located adjustable abutment members in the side walls of said U-shaped recess, cooperating with said arm, a pair of contacts arranged centrally on said guide tube in substantial alignment with the abutment members for controlling the operative circuits of the solenoids, one of said contacts being carried by a projecting portion of the slide member, a contact spring for carrying the other contact of the pair, said contact spring being carried by the guide tube with its contact carrying end portion arranged centrally with respect to the guide tube.

2. In a reciprocating electromagnetic driving device provided with a solenoid having an operative circuit, a movable magnetically permeable core member, a return spring acting on said core member and a circuit making and breaking device controlled by the movement of said core member and controlling the operative circuit of the solenoid, said device comprising a slide member consisting of a flat strip provided with a U-shaped bent portion forming a recess within the said strip, the open side of said bent portion being turned towards the core member and the flat strip and the bottom section of said U-shaped recess forming slide surfaces, said strip being provided with an axial extension, a tubular guide member enclosing said slide member, provided with guiding surfaces for said flat strip and for the bottom section of the bent portion of the slide member and further provided with an opening facing the core member and giving access to the recess of the strip formed by the bent portion of the same, an arm carried by said magnetically permeable reciprocating core member, projecting into the recess of the slide member through said opening and engaging the side portions of the U-shaped bend portion, a lateral projection on said tubular guide member, a contact spring carried by said lateral projection and projecting towards the central axis of said tubular member, a fixed contact on said contact spring arranged in the longitudinal axis of said tubular guide member, and a movable contact cooperating therewith carried by the axial extension of said slide member and arranged substantially in the axis of the guide member, said pair of contacts controlling the intermittent energization of the solenoid core.

3. In a reciprocating electromagnetic driving device, provided with a solenoid, having an operative circuit, a movable magnetically permeable core member, a return spring acting on said core member and a circuit making and breaking device controlled by the movement of said core member and controlling the operative circuit of the solenoid, said device comprising a slide member consisting of a flat strip extending in and movable in a direction substantially parallel to the path of the reciprocating magnetically permeable core member, said slide member being provided with a bent U-shaped portion having a bottom section parallel to the flat portion of the strip and side walls at an angle thereto, the open side of the bent U-shaped portion of the flat strip facing the reciprocating magnetically permeable core member, the flat strip and the bottom section of the bend portion forming slide surfaces, a closed tubular guide member enclosing said slide member and provided with an opening on the side facing the core member for giving access to said U-shaped portion of the strip and further provided with guiding surfaces for said flat strip and for the bottom section of the U-shaped portion parallel thereto, a transverse projection on said tubular guide member, a loose movable spring member within said guiding tube member, between the same and the slide member for pressing the slide member against the guiding surface of the said movable guide member, adjustable abutment members in the side walls of the U-shaped recessed portion of

the slide member, arranged substantially in the longitudinal axis of the tubular guide member, an arm attached to the magnetically permeable core member, projecting through the opening in the tubular guide member into the bent U-shaped portion of the slide member for cooperation with the axial abutment members, a contact spring supporting a stationary contact, arranged on the transverse projection of said tubular guide member, projecting towards the longitudinal axis of the said tubular guide member and the movable contact cooperating therewith and mounted on the slide member, both contacts being arranged for axial relative movement substantially in the longitudinal axis of the guide member and controlling the intermittent energization of the solenoid coil.
